UNITED STATES PATENT OFFICE.

CLARENCE A. HESSER, OF NEWBERN, NORTH CAROLINA.

LOGGING-CAR.

1,252,435.

Specification of Letters Patent.

Patented Jan. 8, 1918.

Application filed May 31, 1917. Serial No. 172,030.

To all whom it may concern:

Be it known that I, CLARENCE A. HESSER, a citizen of the United States, residing at Newbern, in the county of Craven and State 5 of North Carolina, have invented certain new and useful Improvements in Logging-Cars, of which the following is a specification.

This invention relates to attachments for 10 railroad cars and more particularly to an attachment for a logging car.

The primary object of the invention is to 15 provide a device for engaging and holding the standards which retain the logs on the car in a manner that will permit the standards to be released whereby the logs may be permitted to roll off without danger to the workmen engaged in the unloading operation.

20 The invention has for another object to provide a locking mechanism mounted on each of the logging car bolsters and so associated with a chain and a retaining plate as to permit the standards to be held against 25 accidental displacement until such time as the locking mechanism is released.

Another object of the invention is to provide a device of this character that may be released from a point at the side of the car, 30 opposite to that from which the logs are to be ejected, the unloading operation being accomplished with a minimum of exertion by the workmen and with the least possible danger of injury.

35 A further object of this invention is the provision of a logging car which consists of comparatively few parts and is simple in construction, but durable and well adapted to withstand the rough usage to which devices of this character are ordinarily subjected.

40 For a full description of the invention and the advantages and merits thereof, reference is to be had to the following description and the accompanying drawings, wherein is illustrated the preferred form of my invention, in which;

45 Figure 1 is a fragmentary side elevation showing the device attached to a car bolster and engaged with an upright standard, part 50 of the device being broken away to dispose the operating mechanism.

Figure 2 is a top plan view of the device.

55 Figure 3 is a section on the line 3—3 of Fig. 1.

Fig. 4 is a section on the line 4—4 of Fig. 1.

Fig. 5 is a section on the line 5—5 of Fig. 1.

Fig. 6 is a detail fragmentary elevation 60 of a portion of the device.

Referring to the drawings wherein is illustrated the preferred form of my invention and in which like characters of reference indicate corresponding parts throughout the several views, the car platform A is supported on the usual stringers B. Upon the platform of logging cars of this character is generally mounted a plurality of bolsters one of which is indicated at C. 65 These bolsters are employed to mount the logs upon the car when the logs are in transit. For the purpose of retaining the logs in position when they are piled upon the bolsters, it is necessary to provide 70 standards equally spaced along each side of the car and one of these standards is indicated at D.

As shown in Figs. 1 and 2 of the drawing, 75 the bolster C is provided at one end with a pair of spacing blocks 1 and 2 to which is attached a plate 3 so that the plate is spaced away from the side of the bolster to form a pocket 4 open at its end. Received in this pocket is a tongue 5 which has a notch 6 80 formed in its upper edge. One end of the tongue has a finger 7 which projects forwardly from the pocket 4 and is looped to receive an eye 8 attached to a retaining plate 9. This retaining plate is connected to a 85 link pivotally mounted on the opposite side of the bolster C and it will be obvious that when the tongue 5 is released from the pocket 4 the plate 9 will be permitted to swing outwardly to disengage the stand- 90 ard D.

Pivotedly mounted in the pocket 4, on a pivot pin 10 journaled in the bolster, is a latch lever 11 having a bit 12 adapted to register with the notch 6 when the opposite 100 end of the latch lever is raised as shown by full lines in Fig. 1 of the drawing. This end of the latch lever 11 projects rearwardly into a space 12 formed between a plate 13 and the side of the bolster C, the plate being 105 mounted upon and fixed to a spacing block 14 and depending therefrom to the surface of the platform A. This structure is clearly shown in Fig. 4 of the drawing. A complementary latch lever 14 also has one of 110

its ends projecting into the space 12 and its opposite end pivotally supported by pivot pin 15 journaled in the bolster C. This end of the latch lever 14 is protected by pocket 5 16 formed by plate 17 mounted upon two spacing blocks 18 shown to advantage in Fig. 1 of the drawing where the plate 17 is broken away. The lowermost block 18 has a beveled edge 19 to receive the lower 10 edge of the latch lever 14 when the latter drops to the position shown by dotted lines in Fig. 1. This lever is also notched as at 20 and the wall of the notch engages the proximate edge of a key 21, the latter being 15 of a size to fit snugly in the space between the lever 14 and the proximate edge of the spacing blocks 18. The key 21 is connected by a link 22 to a chain 23 which is extended forwardly and upwardly at an angle and 20 embraces the standard D at a point above the plate 9 from which point it extends around the standard and is connected to a cleat 24 mounted on the opposite side of the bolster.

25 As will be apparent from the full lines in Fig. 1, the overlapping ends of the levers 11 and 14, within the space 12, are held in operative position by a sliding supporting bolt 25. This bolt extends through the bolster C 30 from the side opposite to the levers and projects into the space 12 and through a convenient opening in the plate 13. The opposite end of the bolt is pivotally connected to the arm 26 of an operating crank which includes the elongated bar 27 rotatably supported in the bearings 28. This bar extends along the side of the bolster C to the opposite end thereof where it is provided with a depending handle 29 held in inoperative position by pivoted clip 30 which, as shown in Fig. 6, may be swung upwardly to released position.

It will be understood that a series of these devices may be mounted upon certain of the 45 car bolsters to retain the standards D in position for preventing displacement of a load of logs. When in operative position the parts are in position as shown by full lines in Fig. 1 in the drawing. To release 50 the standard in order that the logs may be permitted to roll from the car, it is merely necessary to swing the clip 30 to the position shown by dotted lines in Fig. 6 and pull outwardly on the handle 29 thus swinging 55 the arm 26 to withdraw the latch levers 11 and 14. The lever will then immediately swing down into position as shown by dotted lines in Fig. 1 and, by virtue of this movement, the tongue 5 and the key 21 will 60 be permitted to move out of this position in its corresponding pocket. Since this operation is accomplished from the side of the car opposite to that from which the logs are to be unloaded, it will be apparent that no 65 danger to the workmen will be in evidence.

It is also to be noted that the device may be used equally as well upon logging trucks and sleighs such as are used in logging camps in conveying the logs from the source of supply to the railroad.

From the foregoing it will be observed that a very simple and durable logging car has been provided, the details of which embody the preferred form. I desire it to be understood however, that slight changes in 75 the minor details of construction may be made without departing from the spirit of the invention or the scope of the claims hereunto appended.

I claim—

1. In a log retaining device the combination with a bolster and a standard to be releasably held thereto, of a pair of latch levers pivotally mounted on the bolster, and means carried by the bolster and adapted to 85 embrace the standard and be engaged by one of the said levers to releasably hold the standard against the bolster.

2. In a log retaining device, the combination with a bolster and a standard to be releasably held thereto, of a pair of latch levers pivotally mounted at their outer ends, their proximate ends being overlapped, means to releasably hold the overlapped ends of the latches in raised position, retaining 95 means embracing the standard and adapted to be releasably held by one of the said latch levers and to be released when the said first mentioned means is operated to permit the overlapping of the latches to be released. 100

3. In a log retaining device, the combination with a bolster and a standard to be releasably held thereto, of a pair of latch levers pivotally mounted on the bolster and having the proximate ends in close proximity, means carried by the bolster and embracing the standard and engageable by one of the latches to hold the said means in engagement with the standard, and means for operating the said latches. 110

4. In a log retaining device, the combination with a bolster and a standard to be releasably held thereto, of a pair of latch levers pivotally mounted on the bolster and having the proximate ends in close proximity, means carried by the bolster and embracing the standard and engageable by one of the latches to hold the said means in engagement with the standard, the said proximate ends of the latches being adapted to 115 swing and having means normally holding them against dropping, and means to release the said latches to permit them to drop.

5. In a log retaining device, the combination with a bolster and a standard to be releasably held thereto, the said bolster having a pocket provided near the said standard, a second pocket provided on the bolster and spaced from the first said pocket, means embracing the said standard to hold the 125 130

- same in engagement with the said bolster, the said means including a tongue projecting into the said first mentioned pocket, and a pair of latch levers one of which releasably engages the said tongue, one of the said latch levers being pivoted in each pocket. 5
6. In a log retaining device, the combination with a bolster and a standard to be releasably held thereto, the said bolster having a pocket provided near the said standard, retaining means embracing the standard and including a finger projected into the said pocket, a latch lever pivotally mounted in the pocket and having one end engageable with the tongue, and adapted to swing out of engagement when the opposite end of the lever is dropped, and means to releasably hold the said last mentioned end of the lever in raised position. 10
7. In a log retaining device, the combination with a bolster and a standard to be releasably held thereto, the said bolster having a pocket provided near the said standard, retaining means embracing the standard and including a tongue projected into the said pocket, a latch lever pivotally mounted in the pocket and having one end engageable with the tongue, and adapted to swing out of engagement when the opposite 15
- 20
- 25

end of the lever is dropped, and means to 30 releasably hold the said last mentioned end of the lever in raised position, the said lever including a bit, the said tongue being provided with a notch adapted to receive the said bit. 35

8. In a log retaining device, the combination with a bolster and a standard to be releasably held thereto, a pair of latch levers having their proximate ends overlapped and their remote ends pivotally connected to the 40 bolster, the said standard having a retaining element fixed to one end of the bolster and embracing the standard to be engaged at its opposite end by one of the said levers, a flexible retaining element also embracing 45 the standard and provided at one end with a key engageable by the pivoted end of the other lever, and means to releasably hold the said levers in position to secure the said retaining element and the said key in engagement with the levers. 50

In testimony whereof I affix my signature in presence of two witnesses.

CLARENCE A. HESSER.
